UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,635, dated September 11, 1894.

Application filed August 3, 1894. Serial No. 519,380. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification.

The design consists of a series of ornamental scrolls forming shield-like ornaments placed at uniform distances apart, and containing small ornaments in the center as represented in the accompanying drawing.

The border or upper portion of the design is formed of a series of ornamental scrolls form-

ing panels in which are placed shield-like ornaments, and similar shield-like ornaments also connect the ornamental scrolls which form said panels as shown in the drawing.

What I claim is—

The design for wall paper herein shown and described.

Witness my hand this 31st day of July, 1894.

CHARLES BOOZE.
